DEMODULATOR SYSTEM

Emile Labin, New York, and Donald D. Grieg,
Forest Hills, N. Y., assignors to Federal Telephone
and Radio Corporation, New York, N. Y.,
a corporation of Delaware

Application September 1, 1945, Serial No. 614,078

4 Claims. (Cl. 179—15)

1

This invention relates to multi-channel communication systems and more particularly to multi-channel systems employing a plurality of series of pulses wherein each series represents a signalling channel and the pulses of the different series are interleaved into a single train of pulses for transmission.

In our copending application for Receiver Systems, Serial No. 565,152, filed November 25, 1944, now U. S. Patent No. 2,465,380, granted March 29, 1949, which is assigned to Federal Telephone and Radio Corporation, we disclose a multi-channel pulse demodulator in the form of an electron beam commutator tube. This demodulator employs a cathode ray or electron beam producing structure and means to cause the beam to sweep through a given movement for coaction with a plurality of channel electrodes to separate and demodulate the signal energy of a plurality of series of time modulated pulses. Each channel electrode may comprise either a collector electrode or a combination barrier and secondary emission electrode arrangement across which the beam is caused to sweep. The time modulated pulses of the different channels are applied in any one of a plurality of ways to control coaction between the beam and each channel output electrode. In the forms described in detail hereinafter, the pulses are applied to key the beam on and off according to the leading and trailing edges of the pulses. The beam is synchronized to the channel period to sweep the channel electrodes once each such period so that the keying on and off of the beam coacts with the channel output electrodes to produce output energy corresponding in amplitude to the time modulation of the input pulses of each channel.

According to the multi-channel beam demodulators of our aforementioned application, a large number of channels may be separated and demodulated by each demodulator by providing a long sweep path for the electron beam with channel output electrodes located along the sweep path. The channel electrodes, however, must not be located so close to each other as to permit carry-over of signal energy by way of the beam from one channel electrode to the next; to present objectionable capacity between adjacent electrodes or to collect secondary electron emission from adjacent channel electrode arrangements. Further, for a given size tube, the number of channel output leads is limited, and the size and therefore the life of the electron collecting electrodes are also limited.

It is one object of this invention to overcome the above mentioned difficulties in multi-channel

2

beam demodulator devices without the necessity of building tubes of great size.

Another object of this invention is to provide a multi-channel demodulator system utilizing a plurality of demodulator tubes each having a much smaller number of channel electrodes than the ultimate number of channels desired.

One of the features of the invention is to provide a plurality of beam demodulator tubes with 10 a limited number of channel electrodes per tube, the channel electrodes being spaced apart a distance sufficient to avoid "cross talk interference" or carry-over of signal energy from one channel to the next, to reduce capacity and inter-collection 15 of secondary electron emission between adjacent channel electrodes and to make the channel electrodes large and sturdy.

A further feature of the invention is to provide means for synchronizing the operation of the 20 25 30 35 40 45 50 55 60 65 70 75 80 85 90 95 100 demodulator tubes, the beams of the tubes being phased in their sweep movements so that the channel separating and demodulating functions of the different tubes occur at different timing in order for the beam to be in proper channel electrode impinging relation upon the occurrence of the pulses of the corresponding channel. The pulses occurring between those of the channels selected may be rendered impotent in a given tube or otherwise blocked as hereinafter described.

The above and other objects and features of the invention will become better understood upon consideration of the following detailed description and the accompanying drawings in which:

Fig. 1 is a diagrammatical illustration of a multi-channel pulse demodulator system according to the principles of this invention;

Fig. 2 is a graphical representation of the signal pulse separation according to the system shown in Fig. 1; and

Fig. 3 is a graphical representation of the time demodulating operation of one of the channels.

Referring to Figs. 1 and 2 of the drawings, a multi-channel pulse time demodulating system 45 is shown for twelve signal receiving channels, 1 to 12, wherein the pulses of channel 1 are distinguished in width for synchronizing purposes. The pulses shown in Fig. 2 are numbered according to the signal receiving channels of Fig. 1. 50 As shown in Fig. 1, three multi-channel demodulators 13, 14 and 15 of the type shown in our aforesaid application are included, although it will be understood that a lesser or greater number may be employed depending upon the number 55 of signal receiving channels to be provided and also the number of signal receiving channels

each demodulator may have. As indicated by way of example, four receiving channels are provided for each demodulator although a greater number may be employed in actual practice.

By applying the train of received pulses from input 16 to a synchronizing pulse selector 17 which may comprise any suitable known form of pulse width discriminator, energy only of the synchronizing pulses 1 will be obtained which, in turn, may be applied to a base wave producer 18 for the generation of wave energy for controlling the sweep movement of the beam of the electron tube 13. For a circular sweep movement, the wave is applied to a phase splitter 19 whereby two sine waves of energy, separated in phase by 90°, are produced for output circuits 20 and 21. These two waves of energy are applied to beam deflecting elements 22, 23 and 24, 25 whereby a circular sweep movement of the beam is produced for each period of the multi-channel train.

It will be understood, of course, that the circular movement is illustrated herein for purposes of illustration only, and that any other type of cyclic sweep movement may be substituted by merely providing the proper sweep potentials for the deflecting elements 22 to 25. For example, the sweep pattern may follow the zig-zag tracing commonly used in television.

The electron tube 13 is provided with a plurality of channel output electrodes or collectors 26, 27, 28 and 29, which correspond in number, in spacing and time position relative the beam movement, to channels 1, 4, 7 and 10. Channels 4, 7 and 10 are each connected to a receiving channel circuit which may include a low pass filter such as indicated at 30 for channel 4, the output of which is applied to any desired utilization circuit such as phones 31. The collector 26 corresponds in position to the synchronizing pulses 1 in the timing of the channel pulses and may be used for providing synchronizing pulse energy for any synchronizing purpose that may be required, for example, it may be used for synchronizing an associated multi-channel transmitter circuit.

The electron tube 13, of course, includes the usual electron gun equipment 32, for producing a beam of electrons which is controlled by grid 33 and suitably shaped by the usual focusing means 34. The grid 33 is provided with a source of biasing potential at 35 which, in the present example, comprises a cut-off biasing value. The multi-channel pulses are applied from input 16 over connection 36 and shaper 37, line 38, condenser 39 and line 40 to control grid 33 to key the beam on and off according to the leading and trailing edges of the pulses. The bias at 35 permits all of the pulses applied to the grid 33 to control energization of the beam. While such operation may be practiced, if desired, the pulses of channels other than channels 1, 4, 7 and 10 occurring while the beam is between output electrodes, it is preferred that the pulses of channel 2, 3, 5, 6, 8, 9, 11 and 12 are blocked at the grid. This blocking may be accomplished in different ways. As shown in Fig. 1, a control wave produced at 41 is applied through condenser 42 to grid 33. The control wave producer 41 receives energy properly phased at 43 from base wave producer 18. The producer 41 includes a frequency multiplier 44, a rectifier 45 and a shaper 46. The output of shaper 46 is applied to grid 33 for selective gate control purposes.

Other systems for blocking the undesired pulses

will be clear to those versed in the art. For example the output pulses of each channel may be used to provide blocking pulses for the associated distributor tube.

The input pulses are preferably shaped by pulse shaper 37 to insure a given amplitude and duration for the pulses prior to application to grid 33. The shaper 37, which may be a known form of multivibrator, is particularly useful in improving the signal-to-noise ratio of the transmission since the re-shaping of the pulses not only minimizes interference occurring adjacent the signal pulses and also clips off any superposed interference, but also, by giving the pulses a given duration, measured, for example, from the leading edges thereof, removes to a large degree variations in duration or time position caused by interference.

While the channel electrodes 26 through 29 may comprise any one of several different electrode arrangements, they may be referred to for the present as electron collectors adapted to collect the electrons of the beam as the beam traverses the areas thereof. For other forms of collectors or electron responsive devices, reference may be had to our aforesaid application.

In the operation of the receiver system of Fig. 1, a train of multi-channel pulses according to those of graph A, Fig. 2, are received over input connection 16. The pulses of the synchronizing channel 1 being of a width greater than the pulses of the other channels, are separated therefrom by the selector 17. The output of the selector 17 controls producer 18 to produce base wave 47, graph B. The base wave output of producer 18 is fed both to phase splitter 19 for production of sweep control potentials, and to phase shifter 43. After proper phasing the wave energy is multiplied in frequency at 44, such as indicated by wave 48, graph B. By full-wave rectification at 45, a cusped wave 49, graph C, is produced. By clipping and amplifying the cusps between amplitude levels 50 and 51 in shaper 46, a control wave 52 is produced. The grid 33 being biased to cut off at a level 53, is controlled by coincidence of the undulations of control wave 52 with signal pulses as indicated in graph E. This coincidence between the undulations of wave 52 and a channel pulse determines the energization of the beam, the energization of the beam of tube 13 being in accordance with the occurrence of the pulses of channels 1, 4, 7 and 10 as indicated in graph F. The pulses of channels 2, 3, 5, 6, 8 and 9 are thus blocked and are not permitted to act upon the beam.

It will be thus apparent that the grid 33 of tube 13 is supplied with pulse energy corresponding to the pulses of channels 1, 4, 7 and 10. The pulses of these channels, or at least channels 4, 7 and 10, being modulated in time position key the beam on for the duration of each pulse thereby causing electron collector action at the corresponding channel output electrodes (26 to 29) for the time interval of coincidence between the pulse energized beam and the collector electrodes.

By reference to Fig. 3, the demodulation action of tube 13 is illustrated for one channel. Graph G represents the pulses of one channel only, three pulses being shown. These pulses are not the ordinary consecutive pulses, but are selected to represent certain pulse positions, pulse 55 representing the extreme displacement position corresponding to the maximum negative potential of the modulating wave. The dotted line 56 rep-

resents the trailing edge of pulse 55 when it is displaced to the opposite extreme or positive potential of the modulating signal. Pulse 57 represents zero modulation of the pulse, that is to say, it is half way between the two extreme positions indicated. Pulse 58 represents the opposite extreme displacement position, such as resulting from the maximum positive potential of the modulating energy.

Graph H represents the sweep potential for controlling the beam. For a circular sweep, another wave potential would be required 90° displaced from the one shown. However, for indicating the cycle of operation of the beam in its sweep, the one wave will be sufficient.

In graph I, three electron collector positions are shown, the three positions representing one electron collector in its recurring relation with the sweep voltage of graph II. Referring first to pulse 57 which corresponds to zero modulating energy, this pulse keys the beam on and off for the duration thereof, thereby causing the beam to occur for the duration of the pulse similarly as shown at 57a, graph I, the duration of the beam coinciding for only half of the duration of the pulse. This produces an output current, the energy of which is represented by the pulse 57b, graph J. Pulse 55, corresponding to the maximum negative modulating potential, keys the beam on and off as indicated at 55a just prior to the coincidence of the beam with the collector 59. Therefore, no current flows in the output circuit for this pulse position. The pulse 58, however, keys the beam on when it is in full coincidence with the collector 59 as indicated at 58a, thereby producing the maximum flow of current in the output circuit of the collector. This is represented by the pulse 58b. Thus, it will be clear that the tube operation not only commutes, that is separates the pulses of the different channels, but also demodulates the time displacement thereof into corresponding amplitude modulated energy.

From the foregoing description, it will be clear that the staggering of the channel pulses between the different receiving or demodulating tubes, greatly lessens the occurrence of interference or cross-talk in the terminal equipment. In pulse time modulation transmission over various communicating links, whether they include repeaters or not, the time displacements of the pulses are kept within predetermined limits and therefore do not overlap or otherwise produce cross-talk between channels. The present invention carries further this freedom from interference into the receiving terminal. The staggering of the channels between the different tubes removes the adjacent channels one from the other and, in the construction of the tubes, reduces to a minimum the capacity between adjacent output electrodes, avoids inter-collection of secondary electron emission between the adjacent electrodes, and at the same time enables the construction of sturdier, longer lasting demodulator tubes of a convenient size.

While we have disclosed the present invention in connection with a specific circuit arrangement, it will be clear that many variations may be made without departing from the invention. It should therefore be clear that the present disclosure is given by way of illustration only and not as a limitation on the scope of the invention as set forth in the appended claims.

We claim:

1. In a receiving system for receiving a multi-

channel train of signal pulses, a plurality of channel selectors, each including means to produce an electron beam and a plurality of output electrodes corresponding to certain of said channels only, means to apply the train of signal pulses to control the energization of the beams of said selectors, and means to cause the beam of each selector to sweep over the output electrodes thereof to cause flow of current in the output circuits in response to the pulses of selected channels only.

2. In a receiving system according to claim 1, further including means to produce control waves according to the channels to be selected by said selectors, and means to apply said control waves to the corresponding selectors to control the operation thereof.

3. In a receiving system for receiving a multi-channel train of signal pulses wherein said train includes synchronizing pulses distinguished in

20 some characteristic from the channel pulses, a plurality of channel selectors, means to apply the train of signal pulses to each selector, means to produce control waves in response to said synchronizing pulses, and means to apply said control waves to cause each selector to select from said train predetermined pulses of a plurality of non-adjacent channels only, each selector including means to produce an electron beam, a plurality of output electrodes, means to cause said beam to sweep said electrodes in accordance with said control waves, the pulses of the train being applied to the beam producing means to control operation thereof in accordance with the occurrence of signal pulses.

35 4. In a receiving system for receiving a multi-channel train of signal pulses wherein said train includes synchronizing pulses distinguished in some characteristic from the channel pulses, a plurality of channel selectors, means to apply the

40 train of signal pulses to each selector, means to produce control waves in response to said synchronizing pulses, and means to apply said control waves to cause each selector to select from said train predetermined pulses of a plurality of non-adjacent channels only, each selector including means to produce an electron beam, a plurality of output electrodes, means to cause said beam to sweep said electrodes in accordance with said control waves, the pulses of the train being applied to the beam producing means to control operation thereof in accordance with the occurrence of signal pulses, means controlled by said synchronizing pulses for producing a blocking wave for each selector and means to apply a blocking wave to the beam producing means of each selector.
